UNITED STATES PATENT OFFICE.

JOHN SCHADE, OF HOLYOKE, MASSACHUSETTS, ASSIGNOR TO NATIONAL BLANK BOOK COMPANY, OF HOLYOKE, MASSACHUSETTS, A VOLUNTARY TRUST ASSOCIATION OF COPARTNERSHIP CONSISTING OF J. W. TOWNE, F. B. TOWNE, E. S. TOWNE, J. M. TOWNE, AND F. W. WILSON, TRUSTEES.

LOOSE-LEAF BINDER.

1,386,428.

Specification of Letters Patent.

Patented Aug. 2, 1921.

Application filed March 23, 1920. Serial No. 368,179.

To all whom it may concern:

Be it known that I, JOHN SCHADE, a citizen of the United States, residing at the city of Holyoke, in the county of Hampden and State of Massachusetts, have invented 5 certain new and useful Improvements in Loose-Leaf Binders; and I do declare the following to be a full, clear, and exact description of the invention, such as will enable others skilled in the art to which it 10 appertains to make and use the same.

This invention relates to certain new and useful improvements in loose leaf binder rings, having particular reference to that 15 style and type disclosed and claimed in my application, Serial No. 327,899, and filed October 2, 1919.

As in the previous application, a ring is employed consisting of an inherently resili- 20 ent coil normally constituting a section of a helix because of its laterally separated or spaced ends and formable into a complete ring by interlocking the ends or terminals.

The principal object of the present im- 25 provement resides in the novel interlock be- tween the ring terminals resulting in a smooth joint and a stronger and securer connection.

In the drawing;

30 Figure 1 is a fragmental view of a loose leaf binder embodying the improved binder rings, one of which is disclosed as being open and the other closed:

Fig. 2 is an edge elevation of my improve- 35 ment in operative position:

Fig. 3 is a radial section through the im- proved terminal interlock or joint thereof:

Fig. 4 is a transverse section thereof on line 4—4 of Fig. 3:

40 Fig. 5 is an edge elevation, partly broken away, of a modified form of ring:

Fig. 6 is a radial section thereof through the interlocking ends:

Fig. 7 is an edge elevation of another 45 modified form of ring with the extremities normally distended, and

Fig. 8 a similar view of such ring showing the extremities interlocked.

The particular form of binder disclosed 50 consists of two covers 1 and an inclosed filler 2 of loose sheets which are perforated with the covers to receive the binding rings

for being bound together in a loose or flexible manner.

The preferred form of ring is disclosed 55 in Figs. 1 to 4 inclusive, and comprises a body 3 of helical form and made of ribbon-like wire of a resilient character and concavo-convex in cross section. In this connection it will be noted that the edges of the 60 ring are rolled over to form a substantially tubular body opened about its outer periphery as shown in Fig. 1. This not only adds strength and reinforcement to the ring but also provides a neat and rounded body lacking sharp, cutting edges. 65

The ends of the binder ring squarely abut each other and one terminal is formed at the inner side of the ring with a recess 4 de- 70 signed to receive, interlockingly, a tongue 5, said tongue being deflected outwardly into the hollow or annular chamber of the ring, as depicted in Fig. 3.

In the modified form the ring 6 is simi- 75 larly constructed with the exception that in cross section the same is convexo-concave and the terminal hook or tongue 7 with its interlocked recess 8 is formed on the outer side of the ring and is deflected inwardly into the hollow interior of the ring. 80

In practice, to open the ring, it is only necessary to pull the ends slightly apart, sufficiently to disengage the tongue from its recess, and then release them when said ends will spread laterally apart owing to the 85 twisting resiliency inherent to the ring. When it is desired to close or render the ring inoperative, the spaced ends are pressed together and slightly pulled circumferentially apart so as to permit the hook or tongue to 90 interlockingly fit the opposing end recess. 95

By this construction the ends of the ring come flush together on a common arc whereby a peripherally smooth joint results with no protruding or projecting edges to catch 100 on the covers and leaves of the loose leaf book. The interlocking tongue is completely housed and protected within the hollow ring and securely holds the ends together against lateral displacement.

While I have shown and described the ring as concavo-convex in cross section so as to form an open channel ring, it will be clear that the edges of the metal may be

brought together in substantial abutment so that in cross section the ring would be tubular, and it is immaterial whether the edges of the metal meet at the inside or the outside of the ring, and therefore I do not limit my invention in this respect.

At Fig. 7 the ring shown has its extremities equipped with interlocking hooks 9, 10, and by forcing the extremities of this ring one past the other these hooks will be readily interlocked by the resiliency of the ring itself, and will present the appearance shown at Fig. 8. This form of interlocking hook ends may likewise be utilized in connection with any of the forms of ring illustrated herein, and I therefore do not wish to limit my invention to any particular form of interengaging elements at the extremities of the ring, the gist of my invention resting in the broad idea of a ring which is a helical segment so that the extremities of the ring may be forced together against the resiliency of the ring and then interlocked so as to present a smooth unbroken area through the entire circuit of the ring.

What is claimed is:—

1. A binder ring made of inherently resilient ribbon-like wire rolled edgewise into tubular form and normally comprising a helical segment whose free ends are formed into interlocking portions.
2. A hollow binder ring made of inherently resilient ribbon-like wire rolled edgewise into tubular form and normally shaped like a helical segment one extremity whereof has a tongue deflected to engage within the opposite extremity when the ends of the ring are forced together for interlocking purposes.
3. A binder ring formed of a single strip of flat resilient metal rolled edgewise into tubular form and having its ends normally

spaced apart after the manner of a segment of a helix, said ends being normally in overlapping relation and provided with portions which interlock when the ends are brought together in a common plane.

4. A loose leaf binder made of flat wire formed tubular in cross section and normally in the form of a segment of a helix the extremities of the ring having complementary portions adapted to interlock whereby all parts of the ring will be in continuous and unbroken arcuate disposition.

5. A loose leaf binder ring in the shape of a helical segment with the ends in overlapping relation and normally spaced apart transversely of the ring and adapted to be forced in endwise abutment in substantially the same horizontal plane, said ring being formed from flat resilient wire whose side edges are rolled toward each other to make the ring tubular in cross section said ends having portions which automatically interlock when such ends are abutted endwise and the ring slightly expanded.

6. A loose leaf binder made of flat wire formed tubular in cross section with the edges disconnected and normally in the form of a segment of a helix the extremities of the ring overlapping each other in the direction of their lengths, and one extremity having a projecting tongue that is bent so as to seat snugly within the other extremity whereby the ends of the ring when forced together in interlocking engagement will abut closely in arcuate disposition in the same plane.

In testimony whereof I affix my signature in presence of two witnesses.

JOHN SCHADE
